UNITED STATES PATENT OFFICE.

WILLIAM G. COUGHLIN, OF PHILADELPHIA, PENNSYLVANIA.

RAIL-SECURING DEVICE.

Application filed April 17, 1928. Serial No. 102,684.

The present invention relates to railways, and more particularly to means for securing rails to their supports.

An object of the invention is to provide a means for securing rails that will firmly hold the rails against movement, longitudinal, lateral or rotative, and at the same time will guard the cross tie against injury resulting from wear, renewal or repair.

The problem of providing a proper support and securing means for railway rails has engaged the attention of engineers and inventors for a long time and in ever increasing degree with increasing traffic and wheel loads. No satisfactory substitute has thus far been found for the wooden cross tie, and the primitive method of securing the rail to the tie by driven spikes is still followed to a large extent. The life of the tie under such conditions is necessarily short, due to the cutting action of the rails and the destruction of the fibers by the spikes originally and in renewing and regauging the rails. To prevent the cutting action of

the rails and to secure a firmer abutment against spreading, metal tie plates have been, and are at the present time, in extensive use. These tie plates have been increased in size from time to time in order to keep pace with the ever increasing wear and loads to which they are subjected, and they have been correspondingly increased in thickness to stiffen them against buckling so as to effect a uniform distribution of the load over the surface of the tie. Hence the tie plates at the present time in use comprise a large volume of metal and are correspondingly costly.

The present invention provides a metal tie plate presenting a large bearing area on the tie, but formed of a minimum amount of metal and yet having a degree of stiffness ample to prevent its distortion under the most trying conditions of use. For attaining this object, I provide a tie plate consisting preferably of a relatively thin plate adapted to rest on top of the tie having depending flanges adapted to engage the sides of the tie. The flanges of course reinforce the plate against bending or buckling in a degree proportional to their depth and they are so formed that the ratio of strength of tie plate to stress at any point is at least equal to the ratio of strength to stress at the point of greatest stress. As the stress is greatest directly beneath the rail the most

economical form of depending flange is one which has a maximum depth directly beneath the rail, and this is a preferred form, although other and widely variant forms come well within the scope and spirit of the invention.

Another object of the invention is to provide, in combination with a tie plate having dependent flanges, devices for holding the rail against longitudinal, lateral, or revolving movement, such devices being so applied that injury to the tie is reduced to a minimum and being so constructed that the rail can be regauged or renewed with great facility without subjecting the tie to the slightest injury.

Referring to the accompanying drawings for a specific description of several forms of tie plates and associated rail holding devices illustrating the present improvements:

Fig. 1 is a side elevation of a tie plate combined with means for holding the plate to the tie and having provisions for adjusting for regauging;

Fig. 2 is a sectional detail taken on line 2-2 of Fig. 1;

Fig. 3 is a side view illustrating more particularly a reinforced holding means for the tie plate;

Figs. 4 and 5 are side and top views, respectively of a tie plate provided with integral lugs adapted to engage the outer and inner edges of a rail base;

Fig. 6 is a side view illustrating the application to the tie plate of a removable clip adapted to engage the inner edge of the rail base, and Fig. 7 is a view looking down on the clip;

Fig. 8 is a side view showing a modified form of adjusting means for regauging;

Fig. 9 is a vertical section on line 9-9 of Fig. 8; and

Fig. 10 is a plan view of Fig. 8.

The various figures illustrate different forms of dependent-flange tie plates. Each consists of a plate 10 adapted to rest on top of a tie under the rail and having a sufficient area to distribute the load over a large surface of the tie, so that the fibers of the latter are not damaged in the use of the tie plate, and each tie plate further consists of a pair of dependent flanges which may engage the sides of the tie. So far as the present invention is concerned these flanges may assume a number of widely variant forms, as long as they so strengthen the tie plate that

the ratio of strength to stress at any point is at least equal to the ratio of strength to stress at the point of greatest stress.

The form of dependent flange 11 illustrated in Figure 1 is perhaps the simplest and most economical. In this form the depth of the flange is a maximum near the center of the plate, or directly beneath the rail, where the plate is subjected to maximum stresses, the depth gradually decreasing towards the ends of the plate in proportion to the decrease of the stresses. In Fig. 3 the depth of the flange 11' is a maximum at the inner end of the plate; and in Fig. 4 the flange 11² has a uniform depth throughout.

Most tie plates are provided with apertures for the passage of spikes engaging both the outer and inner edges of the rail base. As driven spikes are destructive to the fibers of the tie which are essential in resisting bending stresses, it is preferable to combine the tie plates with devices which eliminate the necessity for spikes. The figures show dependent flange tie plates provided with integral lugs 30 struck up from the metal of the flanges and adapted to engage the edges of the rail base to prevent lateral movement, or spreading, of the rails.

The tie plate is preferably formed with a pair of lugs 30 adapted to engage the edges of the rail base and having their ends bent outwardly as shown in Fig. 5 so as to overlie the rail base at an acute angle to the rail. These lugs thus not only prevent spreading of the rails but prevent any substantial longitudinal movement or creeping thereof, since upon the slightest longitudinal movement of the rail in either direction the inwardly bent end of one or the other lug will tend to straighten and consequently will grip the rail more firmly.

In Fig. 1 a dependent-flange tie plate is illustrated in combination with devices for holding the tie plate on the tie so constructed that the fibers of the tie useful in resisting bending strains are not destroyed and the tie plate can be adjusted for gauge with great facility without disturbing said holding means, such devices being of the same general character as those for the same purpose shown in my Patent, No. 1,529,345. The depending flanges of the tie plate may have any suitable form. In this construction the holding means comprise bolts 26 which pass horizontally through the tie near the neutral axis thereof, so that the destruction of the fibers necessary in forming the bolt holes does not substantially impair the strength of the tie as a beam. The bolts 26 pass through horizontally elongated holes 27 formed near the ends of the depending flanges and through holes in rectangular washers 28, the sides of which are located at different distances from the axis of the bolt. The sides of the washers are adapted to abut outward-

ly extending flanges 29 on the depending flanges of the tie plate. Thus the track can be regauged by removing the washers and replacing them with a different side against the flanges 29, the tie plates being moved along the tie correspondingly. It will be observed that the bolts 26 are not disturbed in this adjustment. Any suitable means may be employed for holding the rail on the tie plate, the devices shown for this purpose consisting of hooked lugs 30 disposed at diagonally opposite positions on the tie plate, as illustrated more clearly in Figs. 4 and 5. The tie plates are positioned on the rails, as will be obvious, before bolting to the ties.

If the form of the depending flange is such that two bolts passing through the flanges cannot be used, and it is desired to provide a greater resistance to displacement of the tie plate than that offered by one bolt, the construction illustrated by Fig. 3 may be employed. As here shown, one bolt 26 passes through the depending flanges of the tie plate and is associated with adjusting devices of the same construction as described with reference to Figs. 1 and 2, and a second bolt 31 passing horizontally through the tie is connected to bolt 26 by a strap 32.

Figs. 4 and 5 illustrate a further modification in the means associated with the tie plate for holding the rail against lateral, longitudinal and revolving movement. In the construction here illustrated a pair of lugs 30 are struck up from the metal of the plate at diagonally opposite positions whereby they are adapted to engage the inner and outer edges of a rail base. The free ends of the lugs are bent outwardly so that they overlie the rail base at an acute angle to the axis of the rail, this construction, as before pointed out, preventing any substantial creeping of the rail. In assembling a tie plate having rail holding means of this construction the lugs 30 are engaged with the rail base by holding the tie plate at an angle to the axis of the rail so that the edges of the rail base can pass between the lugs, the plate is then turned to the proper position, at right angles to the rail whereupon the rail base will be snugly engaged by said lugs. The tie plate may be adjustably secured to the tie by devices similar to those illustrated in Figs. 1, 2 and 3.

In the construction shown by Fig. 6, the tie plate is formed with integral lugs 33 adapted to engage the outer edge of the rail base and constructed to prevent creeping, and is combined with removable jaws, or clips, for engagement with the inner edge of the rail base. These clips each comprise a body portion 34 having an edge abutting an outwardly turned flange 35 extending from the inner edge of the depending flange of the tie plate, and having an upwardly extending portion formed with jaws adapted

to receive the inner edge of the rail base, the lower jaw 36 having a horizontal face engaging the under surface of the rail base and the upper jaw 37 being bent outwardly so as to overlie the base at an angle to the rail for the purpose of preventing creeping. The clip may be combined with means for adjusting the tie plate, such means consisting of a rectangular washer 35' having a bolt hole eccentric to the washer, abutting the flange 35 and a bolt passing through the tie and through horizontally elongated holes in the tie plate and the body portion 34 of the clip. It will be observed from Fig. 7 that the body portion 34 of the clip is curved in horizontal section with its concave face opposing the plane surface of the depending flange. Thus, if on account of wear the clip should lose its firm engagement with the rail base, it can again be brought into proper engagement by straightening and taking up some of the curvature of the body portion 34.

Figs. 8 and 9 illustrate a modified form of device for adjusting the tie plate. Adjustment is effected in this modified construction by wedge shaped washers 38 having roughened or serrated edges 39 engaging serrated inclined surfaces of flanges 40 projecting outwardly from the depending flanges of the tie plate. These washers are provided with vertically elongated holes 41, and the depending flanges of the tie plate are provided with horizontally elongated holes 42, said holes being adapted to receive a bolt passing through the tie. Thus by downward displacement of the wedge shaped washers 38 the tie plate may be moved along the tie to any desired position of adjustment. It will be observed that hole 41 is formed in the washer eccentrically. It is intended that the maximum distance between one edge of the washer and the axis of hole 41 shall be equal to the minimum distance between the other edge and the axis of said hole. Thus when adjustment with one edge of the washer has been exhausted the adjustment may be continued from this point by reversing the washer so as to bring its other edge into coaction with the inclined surface of flange 40. In order to increase the resistance to displacement of the washer when clamped in adjusted positions, the faces of the washer may be roughened or corrugated and the surfaces of the depending flanges against which the washers are clamped may be similarly corrugated.

It is to be understood that the invention in its broader aspects is not limited to any specific form of dependent flange tie plate or to any specific means associated therewith for holding the rail against lateral, longitudinal or rotative movement. The forms illustrated and described will indicate the differences in form of which the tie plate

and its associated holding devices are susceptible without departing from the scope of the invention.

Where holding lugs and hooks are shown or described as punched or struck up from side flanges it is to be understood that they can equally as well be struck from the base of the tie plate and vice versa. Likewise, the anti-creeping hooks shown in Figs. 1, 3, 4, 5, 6, 7 and 8 as bent outwardly from the tie plate may be bent inwardly with equal effectiveness.

Having thus described the invention, what is claimed as new and desired to be secured by Letters Patent is:

1. In combination with a wooden cross tie and a rail supported thereby, a tie plate consisting of a plate disposed between the rail and tie and having depending flanges paralleling the sides of the tie and an integral abutment engaging the outer edge of the rail base, and removable clips secured to said depending flanges engaging the inner edge of said base.

2. In combination with a wooden cross tie and a rail supported thereby, a tie plate consisting of a plate disposed between the rail and tie having depending flanges paralleling the sides of the tie and an integral abutment engaging the outer edge of the rail base, and removable clips secured to said depending flanges having portions overlying and underlying the inner edge of the rail base.

3. In combination with a wooden cross tie and a rail supported thereby, a tie plate consisting of a plate disposed between the rail and tie having depending flanges and outwardly extending abutments projecting from the inner ends of said depending flanges, and having two integral lugs projecting upwardly respectively from opposite sides of said plate adapted to engage the outer and inner edges of the rail base, said lugs being bent outwardly to overlie the rail base at acute angles to the axis of the rail, a bolt passing through the tie and through elongated holes in the flanges and eccentric washers on the bolt coacting with said abutments.

4. In combination with a wooden cross tie and a rail supported thereby, a tie plate consisting of a plate disposed between the rail and tie having depending flanges and an integral abutment engaging the outer edge of the rail base, and having outwardly extending flanges at the inner ends of said depending flanges, clips abutting said last named flanges engaging the inner edge of the rail base, a bolt passing through said tie and through elongated holes in said depending flanges and in said clips, and washers eccentrically mounted on said bolt engaging said outwardly extending flanges.

5. In combination with a wooden cross tie

and a rail supported thereby, a tie plate consisting of a plate disposed between the rail and tie having depending flanges and an integral abutment engaging the outer edge 5 of the rail base, and having outwardly extending flanges projecting from the inner ends of said depending flanges, clips abutting said last named flanges and engaging the inner edge of the rail base, a bolt passing 10 through said tie and through elongated holes in said depending flanges and in said clips, and washers eccentrically mounted on said bolt engaging said outwardly extending flanges, said clips having their body portions 15 curved in horizontal section with their concave faces opposed to said depending flanges, for the purpose described.

6. In combination with a wooden cross tie and a rail supported thereby, a tie plate 20 consisting of a plate disposed between the rail and tie having depending flanges and an integral abutment engaging the outer edge of the rail base, and having outwardly extending flanges projecting from the inner 25 ends of said depending flanges, clips abutting said last named flanges having a pair of oppositely arranged rail engaging jaws, a bolt passing through said tie and through elongated holes in said depending flanges 30 and in said clips whereby said jaws may be located at different distances from a vertical plane passing through the axis of said bolt, and washers eccentrically mounted on said bolt engaging said outwardly extending 35 flanges.

7. In combination with a wooden cross tie and a rail supported thereby, a tie plate 40 consisting of a plate disposed between the rail and tie having depending flanges and having two integral lugs engaging respectively the outer and inner edges of the rail base, said lugs having portions bent inwardly to overlie the rail base at acute angles to the rail, said depending flanges having outwardly extending portions projecting from their inner ends and formed with inclined 45 surfaces, washers having inclined edges engaging said inclined surfaces, and a bolt passing through the tie, through horizontally elongated holes in said depending flange and through vertically elongated holes in 50 said washers.

8. In combination with a wooden cross tie and a rail supported thereby, a tie plate

55 consisting of a plate disposed between the rail and tie having depending flanges, said depending flanges having flanges projecting from the inner ends thereof formed with inclined faces, washers having inclined edges 60 engaging said inclined faces, and a bolt passing through the tie, through horizontally elongated holes in said depending flanges and through vertically elongated holes in 65 said washers.

9. In combination with a wooden cross tie and a rail supported thereby, a tie plate 70 consisting of a plate disposed between the rail and tie having depending flanges, said depending flanges being formed with inclined surfaces, washers having inclined surfaces 75 engaging said first mentioned surfaces, and a bolt passing through the tie, through horizontally elongated holes in said depending flanges and through vertically elongated holes in 80 said washers.

10. In combination with a wooden cross tie and a rail supported thereby, a tie plate 85 consisting of a plate disposed between the rail and tie having depending flanges, said depending flanges being formed with inclined serrated surfaces, wedge shaped washers having serrated sides either of which is adapted to engage said serrated surfaces, said washers having vertically elongated holes located closer to one side 95 than to the other and said depending flanges having horizontally elongated holes, and a bolt passing through the tie and through 100 said holes.

11. In combination with a wooden cross tie and a rail supported thereby, a tie plate 90 consisting of a plate disposed between the rail and tie having depending flanges, said depending flanges being formed with inclined serrated surfaces facing outwardly 95 and with serrated portions extending outwardly from said surfaces, wedge shaped washers having serrated faces and sides engaging said portions and surfaces respectively, said washers having vertically elongated holes located closer to one side than to 100 the other and said depending flanges having horizontally elongated holes, and a bolt passing through the tie and through said holes.

In testimony whereof I hereunto affix my signature.

WILLIAM G. COUGHLIN.
